UNITED STATES PATENT OFFICE.

GEORGE LEASK, OF NANAIMO, CANADA.

CORE-LIFTER FOR DIAMOND DRILLS.

SPECIFICATION forming part of Letters Patent No. 650,686, dated May 29, 1900.

Application filed October 27, 1899. Serial No. 735,010. (No model.)

To all whom it may concern:

Be it known that I, GEORGE LEASK, a subject of the Queen of Great Britain, residing at Nanaimo, in the Province of British Columbia and Dominion of Canada, have invented certain new and useful Improvements in Core-Lifters for Diamond Drills; and I do declare the following to be a full, clear, and exact description of the invention, such as will enable others skilled in the art to which it appertains to make and use the same.

The invention relates to rock-drills, and more particularly to that class which are provided with a tubular cutter-head and a core-barrel, in which is mounted a core-lifter which is adapted to grasp the core and remove it when the cutter-head is withdrawn.

To this end the invention consists in certain features of construction and combination of parts which will be hereinafter fully described and claimed.

In the accompanying drawings, Figure 1 is a vertical transverse section of a cutter-head with my improved core-lifter in position. Fig. 2 is a horizontal section on the broken line $x-x$ of Fig. 1. Fig. 3 is an enlarged detail section of one of the gripper-pins.

In the drawings the same reference characters indicate the same parts of the invention. 30 1 denotes the tubular cutter-head, 2 the core-barrel, and 3 the crown, in which the diamond-drill points 4 are mounted.

5 denotes an annular shoulder formed on the inside wall of the cutter-head 1 and on 35 which the valve-casing 6 rests. This casing is provided with two vertical ports 7 and with corresponding lateral ports 8, which connect the interior of the case with the vertical ports 7. The cutter-head 2 is provided 40 with two longitudinal ports 8' 8'', which extend from the ports 7 to the valve-chambers 9, formed in the lower end of the cutter-head.

10 10 denote a series of valve-ports formed 45 in the bottom of the valve-casing, and 12 a ventilator form of disk-valve axially mounted on the stub-bolt 13 and adapted to open or close or partially close the valve-ports 10, as desired.

50 14 designates a tubular valve having a sliding engagement with the valve-casing and held in a closed position by the spiral spring

15 to cut off communication with the valve-ports 8 8, and the upper end of this tubular valve 14 is formed with a conical valve-seat 55 16 to receive the ball-valve 17.

8' 8'' denote lateral ports formed in the valve-casing 6 above the valve 14, and they communicate with longitudinal ports 8' 8'', which extend through the cutter-head, core- 60 barrel, and crown.

18 18 denote diagonal guide-passages extending downwardly from the valve-chambers 9 9 and opening on the interior of the core-barrel 2 to receive the gripper-pins 19 19. 65

20 denotes a valve mounted in the valve-chamber, and its stem is encompassed by a spiral spring 21 to retain the valve in a normally-closed position.

The lower end of the valve-stem 20' has a 70 ball-and-socket connection with the head of the gripper-pins and by this means holds the gripper-pins 19 clear of the core. When, however, the water-pressure is applied to the valves 20, the gripper-pins are forced into 75 place for gripping the core.

In operating the device the ball-valve 17 is removed from the cutter-head and the latter lowered and rotated to perform the boring, and at the same time a current of water is 80 supplied to the drill by means of the valve-ports 10 10. When the boring operation has progressed a sufficient distance, the ball-valve 17 is dropped down in the cutter-head and it rests on the tubular valve 14, closing its axial 85 passage, and the pressure of the column of water overcomes the tension of the spiral spring 15, forcing the valve 14 downward to open the ports 8 8 and permit the water to pass down the ports 7 7, thence downward 90 through the longitudinal ports 8' 8'' and into the valve-chambers 9 9, thereby opening the valves 20 20 and forcing the gripping-pins 19 19 downwardly and inwardly, so as to encompass and grasp the core, as shown in Fig. 1. 95 The cutter-head is now withdrawn, the upward movement causing the gripping-pins to be drawn still farther out of their guide-passages and wedge said core in the core-barrel, so that it will be removed with the cutter-head.

In boring in soft coal or other soft material the water passing through the valve 12 passes down inside the core-barrel between the core-

barrel and the core. This water will wash away and disintegrate the core in such a way as to render it valueless for determining the nature and exact thickness of the coal passed through, and to overcome this objection when coal or other soft rock is struck and it is desirable to preserve the core the rods are at once hoisted and the disk-valve 12 closed. This shuts the water off the core-barrel and causes it to pass down the longitudinal ports 8³ 8³ directly to the crown.

It will of course be understood that various changes in the form, proportion, and the minor details of construction may be resorted to without departing from the principle or sacrificing any of the advantages of this invention.

Having thus described the invention, what is claimed, and desired to be secured by Letters Patent, is—

The cutter-head provided with longitudinal ports and valve-chambers, the core-barrel provided with diagonal guide-passages communicating with said valve-chambers, the valve-casing mounted in the cutter-head and formed with the lateral ports and the longitudinal ports, the tubular spring-actuated valve and the independent ball-valve, spring-actuated valves mounted in the valve-chambers, and the gripper-pins having a sliding engagement with the core-barrel, substantially as and for the purpose set forth.

In testimony whereof I have hereunto set my hand in presence of two subscribing witnesses.

GEORGE LEASK.
